ABSTRACT

Clip, for pen or any of various articles to be detachably attached to the clothing or the like, which has a stiff support spring-hingedly carrying a gripping arm, with an opening through the support near the head end thereof through which projects a member which, when squeezed down toward the pen body, forces the gripping arm to move out from the pen body and thereby open up the clip.

CLIP

This application is a continuation-in-part of my co-pending application Ser. No. 690,944, filed Dec. 15, 1967.

The invention is an improved clip to be part of a pen, pencil, comb, tie fastener, or other article to be attached to one's clothing or the like. A pen will for simplicity be referred to herein, as a representative article. The invention solves several problems, and most notably offers their solution simultaneously.

The usual clip has to have its grip arm pulled outwardly by hand from the pen. If the clip moves out with little resistance it has little holding power, and one is likely to lose his pen. If the clip is stiff and resistant, either the clip goes onto the pocket with difficulty and wears out the pocket edge, or it is hard to spring out by hand and will sometimes pull the edge of the fingernail from the flesh, and that can be uncomfortable for some time thereafter.

Other forms of clip directed to these problems have been proposed or tried, but they have various disadvantages that have prevented their getting lasting acceptance. Some will not allow the pen to go substantially all the way down into the pocket, some stand out unduly far and will snag on the clothing or interfere with the feel and handling of the pen when it is in use, or are unduly complicated and therefore expensive, or their construction is fundamentally not well adapted to being made into attractive, clean, design effects.

This invention in its preferred form is a clip that swings out to open it, when you push in. You can push it in by squeezing the pen near the top, which is much easier than pulling the bottom of the clip out from the pen while inserting the pen into the pocket or withdrawing it. The distance of travel of the push member and the force required are both moderate. The construction of this invention also has clear space under the grip arm all the way up to the base, so if you choose to locate the base at the top end of the pen the pen can go almost entirely down into the pocket with only the clip visible, if this be desired as it sometimes is. The construction is also free of any protruding part bristling out that might snag and catch on the clothing or feel uncomfortable to the hand when the pen is being used. And—importantly—the construction is such that it is quite capable of being worked into various designs some of which are quite trim and graceful, as is almost an essential today especially in pens made of precious metals that amount to functional jewelry.

The actuation may take the form of a squeeze arranged across the pen surface as in the parent case or a squeezing of part of the clip and the pen body toward each other as shown in embodiments here illustrated. Where a toggle is used the preferred form in this case is a single toggle elbowed arm rather than the double arrangement illustrated in the parent case.

The invention in its preferred forms is accomplished by the use of a solidly secured base at or near the top of the pen, from which a grip arm extends. This grip arm comprises a stiff cantilever support arm from whose lower end a clip swing arm extends, being pivoted at the end of the cantilever support arm and being spring-pressed down against the pen body. The cantilever support arm is open, or apertured, near its upper end; that is to say it has stiff side rods there with open space between them. Protruding up through that open space, but bending back to down within that space at the top end, is a push surface—that can be an actual pushbutton—operatively connected with the swing arm portion to lift it out when the pushbutton is pushed in.

In the drawings:

FIG. 1 is a geometrical diagram of the mechanical action of the toggle-actuated clip.

FIGS. 2 and 3 are two rather similar toggle clips, shown in longitudinal section, mounted on pens.

FIG. 4 is a similar view of a clip incorporating a pushbutton per se.

FIG. 5 is a plan view of a clip similar to those of FIGS. 2 and 3.

2

FIG. 6 is a longitudinal section of a toggle bearing two pushbutton members.

FIGS. 7, 8 and 9 illustrate a one-piece cantilever form of the invention,

FIG. 7 being a plan view thereof,

FIG. 8 a longitudinal section thereof on the line 8—8 of FIG. 7, and

FIG. 9 being a transverse section thereof on the lines 9—9 of FIG. 7.

FIGS. 10 and 11 are respectively a side elevation and a left end view of a two-piece cantilever form of the invention.

The reference character 10 designates a pen body, which could be a pen or a pencil or a comb or a nailfile or a bar member of a tie clip or any article it is desired to clip into or onto one's clothing or the like. For simplicity of expression it will be referred to throughout as a pen, representatively.

A stiff base 12 is stiffly secured to the pen near the head end thereof, that is, the end opposite the writing end during use.

From the base a grip arm 14 arises out from the pen then extends down along it. It comprises first a stiff support arm 16, extending stiffly from the base out a short distance from the pen and a greater distance down along the pen with free clearance between it and the pen, and then a pivot 18 spaced well out from the pen body, and then a swing arm 20 spring-biased down against the pen body. It will be noted that the only motion available here is swinging up or down of the swing arm 20 at the pivot 18. The pivot 18 may range from a pin joint to distributed flexibility, but is preferably a concentrated

flex hinge formed in a continuous arm structure. The clip arm 20 at its free end has a suitable foot 22 which will grip the pocket, etc., between it and the pen body. Spring tension is provided, biasing the swing arm in toward the pen body so it will thus grip the pocket, etc. The flex hinge is formed to be resilient and to have a limited degree of stiffness so it can and preferably does provide this spring biasing.

The grip arm 14 has between base and pivot an elongated aperture 24. This leaves stiff side bars 26, 28 extending longitudinally along, and defining, this opening. The side bars are

heavy rods or are re-enforced with flanges or the like, to keep the support arm 16 stiff notwithstanding the aperture 24.

Between the pen body 10 and the grip arm 14, I provide an elbowed toggle arm 30. This toggle member is made up of a stiff head length 32, which may be curled in section for stiffness, as seen at 33, and a stiff foot length 34 which again is stiffened as by laterally curled construction seen at 35. Between the stiff head length and the stiff foot length the toggle member has a short region 36 that is transversely flat, and which serves as a flex hinge. The toggle member 30 is inserted between the pen body and the grip arm 14, with its flex hinge region 36 extending out through the opening 24. The toggle member is held in place by any of various means. One such means can be the brazing, riveting, or otherwise securing of the end of the toggle's long arm 34 to the end of grip arm 20, near or forming foot 22. It will be noted that the extreme left end 37 of the toggle arm is free to rock or pivot.

The grip arm 20 is so formed as to be resiliently biased toward and against the pen body.

When it is desired to open up the end of the clip, for example to put it over the pocket edge, you press down on the toggle member in the vicinity of its flex hinge region 36. This will swing out the foot, and open the clip.

The action by which this is accomplished is perhaps best understood at FIG. 1. Here the pivot point 37 which is fixed in location is indicated by the same reference character 37. The short head arm 32 of the toggle member is represented by straight line 32. Flex hinge 36 is a pivot point that can move along an arc centered at fixed pivot 37. The long lower arm 34 of the toggle member is represented by straight line 34. Where that member joins the foot 22 there is constituted a flex hinge 23. This is shown in FIG. 1 as a moveable pivot 23, which is free to move on an arc centered at fixed pivot point 18.

In the rest position of the clip, closed in against the pen body, there is a certain straight line length from fixed pivot 37

to moveable pivot 23. When the pivot elbow 36 is squeezed, that is, pushed down, in toward the pen body, and the toggle arm is thus more nearly straightened out, the straight line length from pivot 37 to pivot 23 is increased. Since pivot 37 is fixed, point 23 must move to the right, and it can swing up about the fixed pivot point 37. The right hand end of the arm 20 cannot move direct to the right, but has a locus that extends somewhat to the right in that it can swing up about pivot 18. Thus when the toggle elbow pivot 36 is pressed down to position 36a it forces the moveable foot pivot 23 up to point 23a, thus opening the clip.

It will be observed that there was an inward squeezing motion as between the top part of the pen and the top part of the clip which caused the clip mouth to open, and when it did open it left the space under the clip completely clear all the way up to approximately at the base member, which can be mounted near or at the head end of the pen. It will also be observed that the toggle member is re-entrant at both ends of the opening 24, and thus does not bristle out to possibly snag the clothing.

The elbow pivot and the portions of the toggle member close to it serve as a pushbutton of sorts. This pushbutton effect can be enhanced by brazing or otherwise securing a button proper, as shown at 40 in FIG. 4. This can take many forms. One form that more fully obtains the anti-snagging benefit is that shown in FIG. 6. There two button members 41, 42 are secured to the toggle member immediately to the two sides of the flex hinge 36. Both of these may be used, or either one alone.

These button members may be solid or may be—as shown—of thin metal stamped to form crown and skirt walls at end and sides. In FIGS. 7, 8 and 9 another embodiment of my invention is illustrated. Here a single metal stamping or plastic molding provides stiff base 50, stiff support arm 51 stiffly arising out from the base and extending a greater distance down toward the foot of the pen and providing an elongated opening 52, preferably by branching into two stiff rod members 53. These rod members near their termination make flex hinges 54 by being transversely flat, preferably longitudinally curved, and thin enough to flex resiliently.

To the far side of these flex hinges the rod members join stiff grip arm 55, which has swing arm portion 56 beyond the pivot and push arm portion 57 extending stiffly back to the head side of the flex hinge as a central continuation of it. The entire length of grip arm 55 is preferably centrally crowned or curled to give it stiffness.

Preferably the push arm portion 57 lies over the opening 52 between the two side rod members 52 and on actuation can be pushed down into that opening.

The embodiment illustrated in FIGS. 10 and 11 also has a stiff base 60 stiffly secured to the pen 10. A stiff support arm 62 rises stiffly from that base for a short distance out from the pen and then extends generally parallel to the pen for a greater distance down away from the head end. As it extends down it provides a longitudinally elongated opening 62 which in this case is open at its foot end (save for pivot pin 65, spring 69, or the like). Preferably the opening is central and is flanked by two stiff rods 63 which constitute this part of the support arm 62. This construction can serve as a smooth shroud about a pushbutton member that will be described. Near the end of the rods 63 or other members constituting support arm 62 a pivot 64 is provided, as by pivot pin 65. There a grip arm 66 is pivotally attached. It has head portion 67 serving as a pushbutton and having depending end skirt portion 68 and side skirt portions 69 that extend down just to or just within the opening 62.

The dimension *a* from crown top to skirt bottom of the pushbutton member approximately equals dimension *b* which is the clearance from its skirt bottom to the base below, which may be pen body 10 or the base member 12 as illustrated. Dimension *c* which is the length of the pushbutton or lever arm part is preferably about two to three times the length *d* of the foot portion 68 of the grip arm 66, which extends to the

foot side of the pivot and serves to clamp the pocket cloth. Any desired spring tension means may be used to resiliently urge the foot 69 against the pen body.

It will be observed that with this form also an inward squeezing motion as between the top part of the pen and the pushbutton portion of the clip opens the clip mouth and leaves space under the clip clear for being put over the pocket edge, and—if desired—all the way to the head end of the clip which can be within one or a few millimeters of the head of the pen, and because of the shrouded pushbutton construction there is no bristling part to snag, or to give an undesirable feel in use.

I claim:

1. Clip for pen or the like comprising a stiff base adapted to be stiffly secured to the pen near the head end thereof, a stiff support arm extending stiffly from said base out a short distance from the pen and a greater distance down along the pen with free clearance between it and the pen, a swing arm hingedly secured to said support arm and extending down therefrom, spring tension biasing said swing arm in toward and against the pen body, and a push element toward the head end from the pivot location operatively connected to the swing arm to move the swing arm out when the push element is squeezed and thereby pushed in toward the pen body, and in which the support arm has an elongated opening in it between the base and the pivot in its portion that is extended out a short distance from the pen, and the push element projects above that opening in relation such that it is received within that opening when squeezed down.
2. Clip of claim 1 in which the support arm has an elongated opening in it between the base and the pivot, and the push element projects up and out through and above that opening.
3. Clip of claim 2 in which the push element as it comes back from the pivot region toward the head end of the pen rises above the level of the support arm there and as it approaches the head end of said opening dips down inside said opening.
4. Clip of claim 3 in which the clearance between the lowermost portions of said push element from the pen body and the base below is not less than nor much greater than the amount by which at rest it rises above the level of the apertured support arm whose opening it is received within.
5. Clip of claim 4 in which the push element extends to the left from the pivot by a distance equal to approximately one-third to one-half the length of the swing arm from its pivot point to its foot.
6. Clip of claim 5 in which the push element includes a depending structure constituting at least a skirt extending down from the end and sides of the push element, closing—from above—the opening in the support arm even at rest position.
7. Clip for pen or the like comprising a stiff base adapted to be stiffly secured to the pen near the head end thereof, a stiff support arm extending stiffly from said base out a short distance from the pen and a greater distance down along the pen with free clearance between it and the pen, a swing arm hingedly secured to said support arm and extending down therefrom, spring tension biasing said swing arm in toward and against the pen body, and a push element toward the head end from the pivot location operatively connected to the swing arm to move the swing arm out when the push element is squeezed and thereby pushed in toward the pen body, and in which the push element is a part of a toggle arm assembly that includes a head length and a foot length at an angle to each other and a flex hinge region joining them.
8. Clip of claim 7 in which the end of the foot length is attached to the swing arm near its foot end and the end of the head length is pivotally positioned close to the base.
9. Clip of claim 8 in which the head arm and the foot arm are curled for longitudinal stiffness while between them a short region is flat across for flexing longitudinally.
10. Clip of claim 8 in which a pushbutton member is attached to the toggle arm and projects out above the opening in the support arm.
11. Clip of claim 10 in which the pushbutton member is on the head length of the toggle arm.

12. Clip of claim 10 in which the pushbutton member is on the foot length of the toggle arm.
13. Clip of claim 10 in which there are two pushbutton members close together, effectively forming a single pushbutton, one on the head length and one on the foot length of the toggle arm.
14. Clip of claim 1 in which the parts mentioned are all in-

tegral and two side rods that are part of the support arm hingedly secure the swing arm to the rest of the support arm, these side rods having regions of relatively easy spring flex near where they are attached to the swing arm.

15. Clip of claim 14 in which all parts are longitudinally stiffened except at specified regions of relatively easy spring flex.
